(57) **CLAIM**

The ornamental design for a container cover, as shown.

DESCRIPTION

FIG. 1 is a front perspective view of a container cover in a partially closed configuration with a cup.

FIG. 2 is a front perspective view of the container cover in a partially closed configuration with a cup.

FIG. 3 is a right side elevational view of the container cover in a partially closed configuration.

FIG. 4 is a front perspective view of the container cover in a partially closed configuration.

FIG. 5 is a front perspective view of the container cover in an open configuration.

FIG. 6 is a top plan view of the container cover in a partially closed configuration; and,

FIG. 7 is a front perspective view of a container cover in a fully closed configuration with a cup.

The broken lines in the drawing depict environmental subject matter only and form no part of the claimed design.
